(57) **CLAIM**

The ornamental design for an integrated all-in-one computer, as shown and described.

DESCRIPTION

FIG. 1 is a left front isometric view of a first embodiment of an all-in-one computer constructed in accordance with the present invention;

FIG. 2 is a left rear isometric view thereof;

FIG. 3 is a front elevational view thereof;

FIG. 4 is a rear elevational view thereof;

FIG. 5 is a top view thereof;

FIG. 6 is a left side elevational view thereof; and

FIG. 7 is a right side elevational view thereof.

FIG. 8 is a left front isometric view of a second embodiment of an all-in-one computer constructed in accordance with the present invention;

FIG. 9 is a left rear isometric view thereof;

FIG. 10 is a front elevational view thereof;

FIG. 11 is a rear elevational view thereof;

FIG. 12 is a top view thereof;

FIG. 13 is a left side elevational view thereof; and,

FIG. 14 is a right side elevational view thereof.
